ADZ ATTACHMENT FOR HAMMERS

Leland M. Van Slyke, North Hollywood, Calif.

Application July 19, 1940, Serial No. 346,359

1 Claim. (Cl. 145—29)

My invention relates to a blade attachment for hammers, and particularly to an adz attachment for this purpose.

One of the principal objects of this invention is to provide an adz or other blade attachment for hammers whereby the adz or other attachment will remain connected or attached to the hammer, and particularly in which the adz or other attachment remains resiliently connected or attached to the hammer so that it may yield to unusual distortion, but will at all times be tightly but yieldably connected to the hammer.

Another important object of this invention is to provide an adz or other blade attachment for claw hammers in which the adz or other blade attachment may be securely and yet resiliently held by or attached to the hammer, even though the blade attachment is made very narrow, or the adz attachment is made extremely narrow and substantially the width of the head of the hammer.

A further important object of this invention is the provision of simple means for preventing shavings from becoming lodged between the blade attachment and the head of the hammer.

Also an important object of this invention is to provide a novel, simple, and durable means for resiliently connecting the adz or other blade attachment to the hammer.

An object also of this invention is to provide an attachment of this class which may be conveniently carried in the pocket when not in use, and which may be easily and quickly connected to or detached from the hammer.

With these and other objects in view, as will appear hereinafter, I have devised a novel adz or other blade attachment for hammers, as will be hereinafter described in detail and particularly set forth in the appended claim, reference being had to the accompanying drawing and to the characters of reference thereon, which form a part of this application, in which:

Fig. 1 is a fragmentary view of a hammer having straight claws, showing my blade attachment, in the form of an adz, detachably secured thereto;

Fig. 2 is an inner side view thereof, separate from the hammer;

Fig. 3 is a sectional view thereof, taken through 3—3 of Fig. 1;

Fig. 4 is a fragmentary view similar to that of Fig. 1 but showing the blade attachment on a curved claw hammer;

Fig. 5 is a fragmentary view of an adz attachment secured to a claw hammer but showing a

slightly modified form of the strap connection for securing the attachment to the hammer; and,

Fig. 6 is an inner side view of the adz member of the latter modification.

My adz or other blade attachment, shown in the drawing, is intended to be attached to and used with the conventional straight or curved claw hammer, designated, respectively, 1 in Fig. 1 and 2 in Fig. 4. All of the views of the drawing show adz attachments, that is, in which the blade is positioned transversely with respect to the longitudinal extent of the hammer. The blade is preferably curved in its longitudinal extent, as in the usual adz construction.

The adz blade, designated 11, has a wedge lug 12 at the back or inner side. This lug is positioned at the median line of the adz blade and extends longitudinally with respect to the blade and is positioned nearer the upper end 11^a of the blade than the lower cutting edge 11^b thereof. This lug is provided with a long wedge-shaped cross-section 12^a, as shown in Fig. 2, to receive the outwardly diverging claws 1^a of the hammer 1. This wedge portion 12^a which is wedge-shaped longitudinally with respect to the blade, also has a transverse wedge or dovetail cross-section, as indicated by 12^b in Fig. 3. This wedge or dovetail section 12^b fits into the correspondingly shaped nail receiving recess between the claws of the hammer 1.

The wedge lug 12 may be cast or forged integrally with the blade 11 of steel. The whole tool may then be tempered and the temper drawn from the wedge lug portion.

The construction of the wedge lug of softer material facilitates the fitting of the attachment to various hammers, namely by permitting the opposite sides of the wedge lug to be filed readily to cause the desired fit.

At the inner side of the blade member is a transverse flange 13 which is positioned at the outer end of the wedge lug. This flange 13 provides a relatively wide seat for the end portions and outer side of the claws of the hammer to prevent rocking movement of the blade with respect to the hammer. But this flange 13 performs another important function, namely that of preventing shavings, or the like, from becoming lodged between the blade member and the claws of the hammer. The flange 13 is preferably integral with the blade and wedge lug.

Even though the claws of the hammer grip the wedge lug 12 tightly, use of the adz or other blade attachment causes the latter to be loosened and also the joint between the hammer claws

and wedge lug to wear. To avoid unnecessary play between the hammer and the attachment and also to retain the attachment in its secured position, I have provided a resilient band or strap A, which is secured at its ends to the adz or other blade member and is looped at its intermediate portion around the handle portion of the hammer.

This resilient band or strap consists preferably of a plurality of small-diameter coil springs 21 which are provided at their coincident ends with eyes 22. These eyes may be in the form of screw eyes which are screwed into the ends of the springs. The coincident ends of the springs are encircled, and thus secured together, by metal bands 23. To the eyes at one end of the strap is secured a link or links 24. This link, or the end link, extends through a hole or eye 11^e near one lateral edge of the blade member 11. To the eye members at the opposite end of the strap is secured a link or links 26. This link or the end link is detachably connected to a hook 11^f which is preferably formed in the blade member. The eye or hole 11^e and the hook 11^f are positioned at the opposite sides of the wedge lug 12 and spaced therefrom a distance sufficient to allow the claw portion of the hammer to be inserted therebetween and attached to the wedge lug, as shown in Fig. 2. The eye and the hook are located preferably near the upper end of the blade member, as shown, for rigidly securing the blade member in position.

In order to apply the blade member to a curved claw hammer, a special wedge lug 31 is provided

in which one or the lower end 31^a of the lug is considerably higher and provides a shoulder for the end of the claw hammer considerably spaced from the blade member.

5 In order to permit the construction of a relatively narrow blade member of the adz attachment, as shown in Figs. 5 and 6, the above mentioned eye and hook are arranged, as shown in Figs. 5 and 6, as an eye member 41 and a hook 10 42, which are provided at the outer portion of the wedge lug and are spaced from each other longitudinally with respect to the wedge lug.

Though I have shown and described a particular construction, combination, and arrangement of parts and portions, and certain modifications thereof, I do not wish to be limited to the same, but desire to include in the scope of my invention the construction, combination, and arrangement substantially as set forth in the 20 appended claim.

I claim:

25 In an adz attachment for a claw hammer, an adz member having a cutting edge at one end and a wedge lug at the back side thereof adapted to receive at the opposite sides of the wedge lug the claws of the hammer, said adz member having also a transverse flange adjacent the end of the wedge lug nearest the cutting edge, the outer sides of the claws of the hammer being adapted to rest on the outer edge of the flange, and means for securing the adz member to the hammer.

LELAND M. VAN SLYKE.
